(57) **CLAIM**

The ornamental design for a graphical data display screen with graphical user interface for display of continuous loop insulin and glucose data, as shown and described.

DESCRIPTION

FIG. 1 is a front view of a first embodiment of a graphical data display screen with graphical user interface for display of continuous loop insulin and glucose data; and,

FIG. 2 is a front view of a second embodiment thereof. The evenly spaced broken line showing of the graphical data display screen with graphical user interface for display of continuous loop insulin and glucose data is included for the purpose of illustrating portions of the article and form no part of the claimed design. The outer long dash short dash broken line represents the bounds of the claimed design and forms no part thereof.
